UNITED STATES PATENT OFFICE.

CLAUDIUS REGAUD, OF LYON, FRANCE.

OSMO-ANTICATHODIC VACUUM-REGULATOR FOR X-RAY TUBES.

1,096,390.

Specification of Letters Patent. Patented May 12, 1914.

Application filed April 9, 1912. Serial No. 689,515.

To all whom it may concern:

Be it known that I, CLAUDIUS REGAUD, a citizen of the French Republic, residing at Lyon, in the Republic of France, have invented a certain new or Improved Osmo-Anticathodic Vacuum-Regulator for X-Ray Tubes, of which the following is a specification.

This invention relates to a new or improved osmo-anticathodic vacuum regulator for X ray tubes.

It is known that in the interior of any tubular producer of X rays the operation thereof produces a progressive reduction of the quantity of gas contained therein, the increase in the degree of vacuum causing the phenomenon known as "hardening" of the tube, and in the course of time the said tube becomes unsuitable for electric discharges and for the emission of X rays.

To maintain the tube in a condition for use or operation, it is necessary to compensate the consumption of gas by the introduction or liberation of small quantities of gas, at suitable times into the interior of the tube. Any device which permits of maintaining or reestablishing the necessary pressure of gas within the interior of an X ray tube, is termed a "regulator". It is further known that a plate of platinum (or of certain other metals less frequently employed than said platinum) impervious to hydrogen gas when in a cold condition, becomes pervious to said gas when heated to a sufficient degree. Villard first applied this phenomenon to maintain or reestablish the necessary quantity of gas in the interior of an X ray tube, and his osmo-regulator consists of a platinum tube soldered to the radiating bulb, said tube being closed at its free end and communicating at the other end with the interior of the bulb. When said tube is heated by means of an exterior flame, minute quantities of hydrogen contained in the gas of the flame are caused to enter the bulb.

The improvement which forms the object of the present invention consists essentially in arranging the osmo-regulative platinum member as an anticathode, to conduct the hydrogen on the face of said member which is in communication with the exterior of the tube and in using the heat produced by the cathodic rays to bring said member to incandescence, whereby the use of an exterior flame will be dispensed with and the

regulation of the vacuum will be effected either as desired or automatically by the action of the X ray bulb itself.

The invention can be carried out in several ways, but it is necessary to consider, firstly, examples of various methods of arranging the osmo-anticathodic member and of causing the hydrogen to come in contact therewith, and secondly, the relations which may exist between the osmo-regulative anticathode and the anti-cathode serving for the emission of the X rays.

To consider the first factor, viz. various arrangements of the osmo-anticathodic member and the circulation of gas in contact therewith.

The Figures 1, 2 and 3 of the annexed drawing are sections, and Fig. 3^a a detail view showing examples which may be equally well applied in cases where the osmo-regulative anticathode serves at the same time for the emission of X rays and also to cases where this anti-cathode is exclusively used for regulating purposes. In the latter case the anticathode is housed in a branch communicating with the bulb. In all these figures the parts formed of glass are indicated by fine lines, the various metal parts by less fine lines, and parts of platinum by heavy lines. Fig. 4 is a modification in which the improved cathode is used exclusively for regulating purposes.

In Fig. 1, which relates to the first example, the anticathode comprises a cylindrical nipple *f* of platinum soldered at its edge to a glass tube *b*, which traverses and is fused into the wall of the bulb *a* (or into the branch *b*₁ of the bulb which incloses the regulator). The branch *b*₁ terminates exteriorly in a large orifice surrounded by a metal collar *c* and closed by a rubber plug *k* provided with two holes. A metal wire *e* connects the metal *c* to the platinum nipple *f* with which it is alone in contact, and is adapted to conduct the current (positive pole) from the terminal *d* connected to the high tension conductor, to the platinum nipple (which serves at the same time as an anode). *g* is a glass sleeve surrounding the tube of the anticathode and serving to prevent parasitic discharge. Two glass tubes *h* and *i* traverse the plug *k* for inlet and discharge of the gas respectively. The anticathode *f* is placed opposite the cathode *p* and the latter is so disposed that the cathodic rays directly strike the surface of said

anticathode and heat same. If at this moment hydrogen or illuminating gas (which contains sufficient traces of hydrogen) is conducted through the tube h traces of gas 5 will traverse the anticathode f directly it has reached a sufficient temperature and will decrease the amount of vacuum in the bulb a . The osmose will cease immediately at will according to the arrangement adopted, either by causing the flow of the cathodic rays on the anticathode f to cease or by sweeping away the osmotic gas by a current 10 of inert gas.

In the construction shown in Fig. 2 the 15 anticathode consists of a metal casing 1 having for example the form of a short cylinder. The anticathodic wall f_1 of said casing is formed of a plate of platinum. The remainder of the casing may be formed of a metal 20 other than platinum but capable of being welded thereto. In the rear face of the casing are two orifices which form communications with two metal tubes h and i of small diameter which, connected to one another in 25 the axis of the branch b_1 traverse a metal cap c_1 at the end of said branch and then each open to the exterior. At the parts which traverse the cap c_1 the said tubes may be formed of a metal capable of being securely welded 30 to glass (such as platinum). The two connected tubes h and i serve for inlet and discharge of gas respectively, and further serve both to maintain the anticathode in place 35 and to conduct the high tension current (positive pole) to said anticathode. g and n designate glass sleeves surrounding the anticathode and the tubes h i respectively. The operation of the osmo-regulative anticathode is the same as in the form shown in 40 Fig. 1.

In the construction shown in Fig. 3 which relates to a third example, the anticathode 45 consists of a metal plate s shown in end elevation in Fig. 3^a, on the anti-cathodic surface of which there is arranged by bending same, a platinum tube t . The said tube is continued by or in connection at its two ends 50 with two metal tubes h and i , serving respectively for inlet and discharge of the gas and which behind the anticathode as well as 55 outside the bulb are arranged in a similar manner to the construction described with reference to Fig. 2. The platinum tube t through which the osmotic gas is introduced, is heated directly by the action of the cathodic rays from the cathode p . The metal plate s acts to arrest the cathodic rays which 60 are not encountered by the said platinum tube t .

65 All the arrangements above described only differ from one another by the construction of the osmo-anticathodic surface, the manner in which the same is connected to the wall of the bulb and the means used for the inlet and discharge of the gas, but the

governing principle of operation is the same throughout.

To now turn to the second consideration, viz. relations existing between the osmo-regulative anticathode and the anticathode 70 serving for the emission of the X rays, the various devices above described can be employed in two ways.

In Figs. 1, 2 and 3 the anticathode serving for the regulation is the same as that for the emission of the X rays, in other words, 75 the bulb is provided with a single anticathode producing both the X rays and the regulation. In this case, it is clear that the anticathode must be sufficiently strong to sustain the prolonged shocks of cathodic rays, and must also include or comprise cooling devices necessary to prevent its fusion and destruction during prolonged operation. The bulb being in operation, if it is desired 80 to soften its effect, osmotic gas must be injected through the inlet tube h , and the osmose be arrested by subsequently injecting an inert gas which will sweep away the first 85 gas.

In the second case, which is illustrated in section in Fig. 4 of the drawings, and which would probably be more suitable and most frequently employed, the regulating device is entirely distinct from that for the emission 90 of X rays, the bulb being provided with two cathodes p and two anticathodes f , one cathode and one anticathode serving exclusively for the emission of X rays while another cathode and anticathode serve 95 exclusively for the regulation. In other words the apparatus will comprise two bulbs a a_1 joined together, the larger one a serving for the production of X rays, and the other smaller one a_1 constituting an annex to the 100 first and serving exclusively for the regulation of the bulb producing the rays. Such would be the case for example in anticathodic bulbs cooled by water, as shown in connection with the bulb a .

The details of construction of the regulating bulb and appurtenant parts are shown as similar to those described with reference to Fig. 1, but may be similar to those shown in the other figures if desired.

110 What I claim as my invention and desire to secure by Letters Patent of the United States is:—

1. In apparatus of the class described, in combination, a tube, a cathode therein, an 115 anticathode within said tube, said anticathode being formed of osmotic material and being positioned directly in the path of the electrical discharge from said cathode, and means to conduct a gas into operative relation to said anticathode.

2. In apparatus of the class described, in combination, a tube, a cathode therein, an 120 anticathode within said tube, said anticathode being formed of osmotic material and 125

positioned opposite to said cathode whereby the electrical discharge from said cathode will fall directly upon said anticathode to heat the same, and means for conducting a 5 gas into operative relation to said anticathode.

3. In apparatus of the class described, in combination, a tube, a cathode therein, an anticathode within said tube and formed of 10 osmotic material, electrical conductors connected to said cathode and to said anticathode, and means for conducting a gas into operative relation to said anticathode.

4. In apparatus of the class described, in 15 combination, a tube, a cathode therein, a hollow chamber comprising an osmotic wall forming an anticathode and disposed in the

direct path of the electrical discharges from said cathode and means for introducing a gas into said hollow chamber. 20

5. In apparatus of the class described, in combination, a tube, a cathode therein, a hollow chamber comprising an osmotic wall forming an anticathode and disposed in the 25 direct path of the electrical discharges from said cathode, said hollow chamber being provided with a gas inlet and with a gas outlet.

In witness whereof I have signed this specification in the presence of two witnesses.

CLAUDIUS REGAUD.
